UNITED STATES PATENT OFFICE.

LEON OTTINGER, OF NEW YORK, N. Y.

GAME-SCORING DEVICE.

Application filed October 3, 1923. Serial No. 666,273.

This invention relates to game scoring devices and has for its primary object to provide a simply constructed and inexpensive device for recording the score in card or 5 other games and which is so constructed that the score is displayed so that it can be easily read by all of the persons engaged in the game.

In one embodiment of the invention I 10 provide a suitable base having a frame pivotally attached to one end thereof and in which the score pad or sheet is held. This frame is normally and yieldingly supported in an upstanding angular position with relation to 15 the base so that the score sheet is visible to the players from various angles. In entering the score, the frame is forced downwardly upon the base by a hand of the score keeper and after the score has been entered 20 and pressure of the hand upon the frame released, said frame with the score pad or sheet is immediately returned to its erect or up- standing position.

I also propose in another embodiment of 25 the invention to incorporate the essential feature of my present disclosure in the structure of a box or case in which playing cards are sold.

With the above and other objects in view, 30 the invention consists in the improved game scoring device and in the form, construction and relative arrangement of the several parts thereof as will be hereinafter more fully described, illustrated in the accompanying drawings and subsequently incorporated in the subjoined claims.

In the drawings wherein I have illustrated 35 several simple and practical embodiments of the invention and in which similar reference characters designate corresponding parts throughout the several views:

Figure 1 is an edge elevation showing one construction of the device with the pad or sheet holding frame depressed by the hand 40 of the writer;

Figure 2 is a similar view showing the normal position of the frame after pressure upon the latter is released;

Figure 3 is a front elevation;

Figure 4 is a longitudinal sectional view 45 through a card case or box of a well known type, illustrating another adaptation of my present improvement, the box being closed;

Figure 5 is a similar view showing the approximate position of the score receiving

wall or flap of the box after its release from connection with the box body;

Figure 6 is a longitudinal sectional view 50 of another alternative construction as embodied in a different type of card case or box showing the score receiving wall or panel in its display position;

Figure 7 is a similar view showing the box 55 or case closed with the cards contained therein.

Figure 8 is a longitudinal section through 60 a card case showing another form of the device with the score receiving card or panel disposed in normal position with relation to the body of the case;

Figure 9 is a perspective view of the case 65 or box shown in Figure 8;

Figure 10 is a side elevation showing another alternative construction;

Figure 11 is a rear elevation thereof; and 70

Figure 12 is a horizontal section taken on the line 10—10 of Figure 8.

In playing games, such for instance as bridge, in which two or more players are 75 involved and which requires the keeping of a score, the person delegated as score keeper is annoyed by frequent requests from the other players for information as to their respective scores. It is the primary object and purpose of my present disclosure to provide a convenient means for prominently displaying the game score so that the score keeper may be relieved of this annoyance 80 and to make it possible for each individual player to at any time ascertain his position or standing as well as that of the other 85 players.

To this end, therefore, in one embodiment 90 of the present improvements, I provide a base 5 which may consist of wood, heavy 95 cardboard, sheet metal or other convenient material and if desired, can be ornamentally cut or shaped. To one end of this base a score pad or sheet holding frame 6 is connected by means of a pivot 7, said frame 100 preferably being of equal width with the base 5. The frame may be of any suitable construction so that the score pad or sheet may be inserted from the free end thereof between suitable guides. One or both ends 105 of the hinge rod or pivot 7 is or are provided with a spirally coiled spring or springs 8, one end of which is suitably attached or fixed to the rod 7 while the other end thereof bears against the side or face of the frame 6. 110

which is opposed to the upper surface of the base 5, as indicated at 9.

The score pad 10 held in the frame 6 has suitable indicia printed on each sheet thereof and the surface may be ruled or marked off into a plurality of columns in which the scores of the respective players are to be entered. Of course, it is apparent that instead of a pad or superposed sheets, separate single score sheets may be provided, or on the other hand, in lieu of the frame 6, a sheet of slate, celluloid or other suitable material may be employed upon the surface of which the score can be entered and after the completion of the game, readily erased.

As shown in Figure 2 of the drawing, the spring or springs 8 act to normally and yieldingly hold the frame carrying the score pad or sheet in an upstanding position in angular relation to the base 5. By properly placing the device on the table, the scores of the players entered upon the pad sheet will thus be clearly visible to each player.

As the game progresses from time to time it is necessary for the person delegated as score keeper to enter the scores of the players upon the pad. In so doing, the player presses with his hand carrying the pen or pencil against the outer face of the frame 6 or the score pad therein and forces said frame down to a horizontal position upon the base 5, as shown in Figure 1 against the resistance of the spring or springs 8. After entering the scores on the pad or sheet, pressure is relieved by raising the hand and the spring or springs 8 will, therefore, immediately act to again lift or raise the frame 6 with the score pad to an upstanding or erect position upon the end of the base 5.

When the device is not in use, the frame 6 may be held upon the base 5 by suitable latch means, such for instance as a hook 11 suitably attached to one edge of the base 5 to engage an eye 12 on the edge of the frame 6 at its free end.

In Figures 4 and 5 of the drawings, I have illustrated the essential feature of my present improvements incorporated in a box or case of one well known form in which the playing cards are sold. As shown, the box body 13 is provided at its open end with a closure flap 14, preferably integral with the base wall of the box. This flap has a tab or extension 15. Usually this tab is inserted between the top wall of the box body and the cards contained therein. In the present instance, however, said tab overlies the top wall of the box body and to this tab there is securely attached at one of its ends a sheet of celluloid or other highly glazed material 16 upon the surface of which the scores of the players may be written and easily erased after each game. The top wall of the box has a transverse slit 17 therein through which the free end of

the sheet 16 is adapted to be inserted to extend between said top wall of the box and the cards contained therein. Thus, in the selling of the cards the end flap 14 will be securely retained in its closed position. During the playing of a game, the end portion of the sheet 16 is withdrawn from the slit 17 and due to the inherent resiliency of the cardboard material, the end flap 14 and the sheet 16 will normally assume a position in angular relation to the plane of the box body approximately as indicated in Figure 5 of the drawing. When in this position, the scores entered upon the surface of the sheet 16 can be easily read by the several players. In entering the score, the sheet 16 is merely pressed down upon the top wall of the box body and upon the release of this pressure, returns to its former angular position as shown in Figure 5.

In Figures 6 and 7 of the drawings, I have illustrated my improvements as incorporated in a card box or case of another well known type, in which the case consists of the inner and outer telescoping sections 18 and 19, respectively. The outer section 19 has a separate top wall 20 which may consist of a sheet of celluloid or other suitable material. This score receiving wall or sheet is attached to the edge of the end wall of the outer case section 19 by means of a thin resilient metal strip 21 which normally supports said wall or sheet 20 in an upstanding position relative to the end wall of the case section. Adjacent to the thin metal strip 21, a keeper strip 22 is attached to the underside of the wall or sheet. The inner box or case section 18 which receives the cards is provided upon one wall thereof at its open end with a transversely extending thin metal strip 23 which projects beyond the end edge of the wall and is adapted to engage the keeper strip 22. Thus, it will be seen that in the vending of the cards, when the inner case section 18 with the cards therein is inserted within the outer case section 19, by manually depressing the wall or sheet 20 until it is approximately horizontal with the other side or base wall of the case section, as the two case sections telescope the metal strip 23 finally engages the keeper strip 22, thus holding the wall or the sheet 20 in its depressed position against the action of the spring metal strip 21.

In the playing of the game, the inner case section 18 is withdrawn only to a sufficient extent to disengage the strip 23 from the keeper 22 so that the wall or sheet 20 of the outer case section will be normally held in an upstanding or erect position by the spring strip 21. Card boxes or cases of this type are made of relatively heavy material, and since the two case sections are not wholly dissociated the weight thereof will prevent

the device from being blown by air draughts from the position in which it is placed. In entering the score, the top wall of the inner case section provides a firm foundation for 5 the sheet or wall 20 when it is forced downwardly by the writer to a horizontal position thereon.

In Figures 8 and 9 of the drawings, I have shown a somewhat simpler embodiment 10 of the device in which one side wall of the card box or case is provided adjacent to its permanently closed end with a slit 35 cut therethrough and extending in substantial parallel relation to the end wall across approximately the entire width of the box or 15 case. This slit is adapted to receive one end of the score receiving card or panel 36, said end of the panel being projected within the box or case and having its end edge engaged 20 against the inner face of the end wall of the case substantially as shown in Figure 8 of the drawings. Thus the card is supported in an upright position slightly inclined from the perpendicular. One side of the card 25 will be highly glazed to receive written entries which are erasable therefrom. When the hand of the writer is pressed against the card or panel, it will readily yield and be forced downwardly upon the box or case wall 30 so as to afford a support while the score is being written on said card. Owing to the inherent resiliency of this card or panel, it will be promptly returned to its normal upright position when such pressure is removed. It 35 will, of course, be apparent that this embodiment of my invention may be employed either in connection with a case in the form of a single section as shown in Figure 5 of the drawings, or in connection with that type 40 of card case or box having telescoping sections as shown in Figure 6. In the latter case, the slit 35 will of course be cut in one of the side walls of the outer case section adjacent to its permanently closed end.

45 In Figures 10 to 12 inclusive I illustrate still another alternative embodiment of the device wherein a metal base plate 5' is provided having upstanding lugs 25 formed on the opposite edges thereof adjacent to one of 50 its ends. These lugs are connected by a transverse rod 26 spaced above the base plate 5'.

The metal pad supporting plate 27 is provided on its opposite longitudinal edges at 55 one end thereof with the angularly disposed arms 29 which are pivotally engaged upon the ends of the rod 26. This pad is normally supported yieldingly in the vertically inclined position shown in Figure 8 by means 60 of a wire spring 29 of proper gauge having its intermediate portion extending transversely above the rod 26 and in contact with the rear face of the plate 27. At opposite ends of this intermediate portion the wire 65 extends downwardly and is coiled about the

rod 26, as shown at 30. The end portions 31 of the spring wire are longitudinally extended from the coils 30 and terminate in inwardly directed eyes 32 which bear upon the upper surface of the base plate 5'. At its 70 rear end this base plate is provided with the upstanding flange 33 for a purpose to be presently described.

A pad of score sheets indicated at P which are suitably secured at one of their 75 ends to a relatively stiff cardboard backing sheet C in the usual manner, is adapted to be positioned upon the plate 27, the pad of sheets overlying the front surface of the plate while the cardboard back C is disposed against the rear face of said plate and its lower edge portion inserted between said plate and the transversely extending intermediate portion of the spring 29. Thus it 80 will be understood that this spring serves 85 the double purpose of detachably retaining a pad of score sheets upon the plate 27 and of yieldingly supporting said plate in its normal position. An additional pad of paper sheets P' upon which notes or computations may be made is also adapted to be 90 arranged upon the base plate 5', one end of this pad being inserted beneath the rod 26 and under the end portions 31 of the 95 spring 29 so that these end portions of the spring will be forced upwardly and the in-turned eyes 32 thereof will exert an appreciable downward pressure upon the end of the pad to thereby hold the same securely 100 on the base plate 5'. In the use of this form 105 of my invention, in entering the score upon the pad P, the pressure of the writer's hand forces said pad and the plate 27 downwardly against the action of the spring coils 30. The spring wire is, however, of such gauge 110 that relatively slight pressure is necessary to force the pad downwardly to a horizontal position, at which time the cardboard backing pad engages the upper edge of the flange 115 33 on the base plate. Upon release of pressure the pad and the plate 27 are immediately returned to their former position.

From the foregoing description considered in connection with the accompanying drawings, the several constructions 115 which I have herein described will be readily understood. In each case, it will be seen that the score card or sheet is conspicuously displayed so that each player 120 may readily observe the same and ascertain the respective scores, thereby making it unnecessary for the player to request such information from the person delegated to keep the score. The construction shown in Figures 1 to 3 of the drawings is exceedingly simple, and can therefore be manufactured and sold at small cost. Also in those constructions wherein the present improvements are embodied in the structure of 125 the box or case in which the cards are 130

vended, in view of the simple character of such constructions, the production cost of such card cases or boxes will not be materially increased. If desired, a flat lead pencil 5 or clip may be inserted within the card case.

I have herein shown several adaptations of my present invention which I believe to be entirely practical and satisfactory in actual use. It will nevertheless be understood 10 that it is possible to incorporate the essential features of the above disclosure in various other alternative constructions and I accordingly reserve the privilege of adopting 15 all such legitimate changes as may be fairly embodied within the spirit and scope of the invention as claimed.

I claim:

1. A game scoring device consisting of inner and outer telescoping sections, said outer 20 section having a relatively movable wall or panel upon which the game score is adapted to be written, resilient means for said panel for yieldingly sustaining the same in a normal score displaying position, said means 25 yielding under pressure whereby the panel may be depressed for the purpose of making

written entries of the game score and said panel adapted to be held down on the inner and outer sections when in their telescoped position.

2. A box or case for playing cards consisting of inner and outer telescoping sections, said outer section having a relatively movable wall or panel upon which the game score is adapted to be written, resilient means connecting said panel at one of its ends to one wall of the outer case section and yieldingly sustaining said panel in a normal score displaying position, said means yielding under pressure upon the panel whereby the latter may be depressed upon one wall of the inner case section for the purpose of making written entries of the game score, and said wall of the inner case section and said panel having coacting means to retain said panel in the latter position.

In testimony that I claim the foregoing as my invention, I have signed my name hereunder.

LEON OTTINGER.
